UNITED STATES PATENT OFFICE

JAMES E. MYERS, OF WHITEFISH BAY, WISCONSIN

HUMIDIFIER AND HEATER

Application filed March 16, 1931. Serial No. 522,978.

This invention relates to an improved humidifier and heater.

One of the objects of the present invention is the provision of an improved type of humidifier and heater which is adapted for use in regulating the humidity of a room or building and, at the same time, giving off enough heat to increase the temperature thereof and also to provide a device which is portable so that the same can be moved about from one room to another in a building and used wherever desired.

Another object of the present invention is the provision of a portable humidifier and heater which includes in its construction a heater for heating water in a suitable tank to provide the proper amount of moisture and a supply tank for the first tank, together with means for automatically cutting off the heater when the water in the supply tank is lowered to a predetermined level, and indicating means to disclose the fact that the water level has reached a predetermined point and the heater cut off.

A further object of the present invention is the provision of a combined humidifier and heater which includes a portable housing having arranged therein, a water supply tank and a heating tank, together with a heater arranged in close proximity to the heating tank, so that the water can be heated to a temperature to give off sufficient moisture for changing the humidity of a room or building and at the same time radiating sufficient heat to increase the low temperature in the room. Attention is directed to the fact that the device includes means for automatically cutting off the heater when the water supply reaches a predetermined level.

With the above and other objects in view, the invention consists in the novel features of construction, the combination and arrangement of parts hereinafter more fully set forth, pointed out in the claims and shown in the accompanying drawings wherein:

Figure 1 is a vertical sectional view of my improved humidifier and heater, illustrating parts thereof in elevation;

Figure 2 is a detailed section on the line 2—2 of Figure 1.

In the construction of a device of this character, I provide a frame work 1 which is supported upon suitable brackets 2 carrying rollers 3 whereby the device can be readily moved from place to place. At the back and both sides of the frame, I provide panels 4 which not only enclose the mechanism within the frame, but also presents a neat appearance to the exterior of the device.

In the front of the device, I provide a comparatively short panel 5, and an upper panel 6 carrying grille work 7 through which the humidified air from the interior of the housing passes into the room or building in which the device is located. Supported within the housing formed by the frame and the panels, is a main supply tank 8, carrying angular brackets 9 and 9' which are adapted to cooperate with similar brackets 10 and 10' carried by the panels for supporting the supply tank 8 within the housing.

The supply tank is provided with an upwardly projecting conduit 11 having a funnel-shaped mouth 12 at its upper end adapted to be disposed directly below the opening 13 formed in the top member 14 for the frame. The opening 13 is normally closed by means of a hinged door 15 which can be swung open to permit the tank 8 to be filled through the conduit 11.

Arranged within the body of the device and supported therein by means of the bracket 16 is a heating tank 17, the upper end of which is opened, as illustrated in Figure 1, and this tank communicates at its upper and lower ends with the tank 8 adjacent its upper and lower ends by means of the connecting conduits 18, so that the water level in the two tanks will remain the same, and the supply of water in the tank 17 will be replenished from the tank 8.

Arranged within the body and supported adjacent the heating tank 17 is a heater 19, preferably in the form of an electric heater having laterally disposed pins 20 projecting from each end thereof, as shown in Figure 2,

with their outer ends laterally disposed as shown at 21 and adapted to be fitted within suitable bearing sleeves 22, carried by the opposed side panels for the housing.

Arranged at one side of the tank is a plate 23, the upper end of which is disposed at an angle, as shown at 24, and is connected to the frame 1 above the grille panel 6. Through this arrangement, it will be apparent that the inclined portion 24 of the plate 23 causes the heat and vapor arising from the heater 19 and tank 17 to pass outwardly through the grille 7 and into the room or building in which the device is located.

However, the vapor from tank 17 striking the inclined portion 24 will cause a certain amount of the vapor to condense and this will run down onto the plate 23 and into the transverse trough 25 at the lower end thereof to prevent the drippings from coming in contact with the surface on which the device is located. Therefore, the device may be placed in a room on rugs, or the like, and the condensed vapor will be prevented from dripping onto the rugs by means of the trough 25.

In order to retain the heat from the tank 8, an insulating member 26 is positioned between the side wall of the tank and the plate 23. Pivotaly mounted within the tank 8 is a rockable arm 27 having a float 28 at one end thereof, with a link 29 pivotally connected to the other end. This link is connected to the throw-arm 30 of a switch mechanism 31. This switch mechanism is connected up with a heater 19 so that when the float 28 drops downwardly to the dotted line position shown in Figure 2, the switch will be actuated to cutoff the heater 19.

In order to indicate the cutting off of the heater, a suitable light 32 is arranged in the circuit with the switch, this light being visible from the exterior of the body, so that a person operating the device can readily ascertain when the water in the tank has fallen to a predetermined level for replenishment and the heater 19 cut-off. The manually actuated throw-lever 33 is arranged upon the exterior of the housing so that the switch 31 can be manually actuated when it is desired to cutoff or turn on the heater 19.

The frame 1 is cut away at the front of the device just above the grille panel 6 to provide an air vent 34 whereby any heat within the upper part of the body will be conveyed outwardly through the vent 34 by means of air circulating up through the bottom of the body. From the above, it will be apparent that I have provided a simple and inexpensive unit which can be used as a humidifier and a heater, and is mounted for transportation from room to room of a building so that the same can be used for changing the humidity of the air in the room and at the same time assist in increasing the temperature thereof.

The device is extremely useful in view of

the fact that it can be turned on and without any attention whatever, will be automatically cutoff when the water supply thereof drops to a predetermined level, which will be indicated by the signal light 32.

I claim:

1. A device of the character described including a housing, a water supply tank removably mounted therein, traction means for supporting said housing, a heating tank within the housing, a heater removably mounted within the housing and supported adjacent the heating tank, a baffle plate at one side of the supply tank having an inclined upper end portion, a receiving trough at the lower end of said plate, said housing having an opening adjacent the heating tank whereby the heat from the heater and the vapor from the heating tank will be guided through the opening by the inclined upper portion of the baffle plate, a switch for controlling the heater, and means actuated by the movement of the fluid in the supply tank for actuating said switch.

2. A device of the character described including a housing, traction means supporting said housing, a water supply tank therein, a conduit leading into the top of said tank having a funnel-shaped mouth, the top of said housing having an opening, communicating with the mouth on the conduit, a heating tank within the housing, said housing having an outlet adjacent the heating tank, a baffle for guiding the vapor from the heating tank through the outlet, a heater adjacent the heating tank, a switch for controlling the heater, a pivoted arm in the supply tank, a float at one end of said arm, and means connecting the other end of said arm to the switch whereby to cut off the heater when the water in the supply tank reaches a predetermined low level.

3. A humidifying and heating device for rooms comprising a casing having an outlet in one wall thereof, a main liquid supply tank arranged wholly within said casing, a relatively small hot water tank arranged in the housing having its upper end open and arranged adjacent to and directly below said outlet, means arranged in the casing for heating the hot water tank, a shield arranged in the casing disposed between the main tank and the hot water tank having its upper end extending over the hot water tank and secured to the mentioned wall of the casing directly above the outlet, and means for supplying the hot water tank with water from the main tank.

In testimony that I claim the foregoing I have hereunto set my hand.

JAMES E. MYERS.
